UNITED STATES PATENT OFFICE

132,911

DESIGN FOR A HEATING RADIATOR

Charles W. Good, Erie, Pa., assignor to Weil-McLain Company, Erie, Pa., a corporation of Delaware

Application December 4, 1941, Serial No. 104,457

Term of patent 14 years

To all whom it may concern:

Be it known that I, Charles W. Good, a citizen of the United States, residing at Erie, in the county of Erie and State of Pennsylvania, have invented a new, original, and ornamental Design for a Heating Radiator, of which the following is a specification, reference being had to the accompanying drawing, forming a part thereof.

Figure 1 is a front elevational view of a heating radiator embodying my new design.

Fig. 2 is an end view of the radiator.

Fig. 3 is a top plan view of said heating radiator.

I claim:

The ornamental design for a heating radiator, substantially as shown.

CHARLES W. GOOD.
